UNITED STATES PATENT OFFICE

JOHN LANZ, OF NEW HAVEN, CONNECTICUT, ASSIGNOR, BY MESNE ASSIGNMENTS, TO THE A. C. GILBERT COMPANY, OF NEW HAVEN, CONNECTICUT, A CORPORATION OF MARYLAND

FAN BASE

Application filed January 28, 1927. Serial No. 164,367.

This invention relates to switch bases for electric fans or the like, and has particular reference to a switch and rheostat construction adapted to be mounted within hollow standard which supports the fan, the construction being relatively simple and inexpensive and applicable to other apparatus where such means for controlling an electric current are required.

One of the objects of the invention is to furnish an efficient and reliable rheostat which can be produced at a minimum cost.

Another object of the invention is to provide an improved means for mounting the rheostat and switch on a suitable base, and for mounting the assembled rheostat and base within the hollow standard of the fan with which the device is to be used.

To these and other ends the invention consists in the novel features and combinations of parts to be hereinafter described and claimed.

In the accompanying drawings:

Fig. 1 is a side elevational view of a fan base or standard, embodying my invention;

Fig. 2 is a view similar to Fig. 1, showing the rheostat and switch base, the fan standard being shown in dotted lines;

Fig. 3 is a view of the rheostat and switch base taken at right angles to that shown in Fig. 2;

Fig. 4 is a top plan view of the rheostat and switch base;

Fig. 5 is a bottom plan view of the switch base and rheostat;

Fig. 6 is a sectional view on line 6—6 of Fig. 3;

Fig. 7 is a sectional view on line 7—7 of Fig. 1;

Fig. 8 is a diagrammatic view of the electrical connections.

The device which I have selected to illustrate and describe as a preferred embodiment of my invention, comprises a hollow standard 10, adapted to support a fan or other electrical apparatus, the standard being closed at the bottom by means of a plate of sheet metal or the like 11. At its lower edge, the standard is provided with a horizontally extending peripheral flange 12, which is

provided with perforations adapted to register with perforations 13 in the base plate 11. The base plate may be conveniently connected to the standard by bushings or the like 14, passed through these perforations and having expanded upper and lower ends 15 and 16 to engage over the material of the base plate and flange surrounding the openings. These bushings or plugs may be conveniently formed of some soft and pliable material as rubber, so that they may be molded in permanent form and thereafter be sufficiently compressed or distorted at one end so as to pass through the openings, and thereafter expand to engage the edges of the openings to properly hold the parts together. In this instance, the lower ends of these plugs or bushings also serve as feet upon which the fan may rest. Due to the nature of the material of which they are made, they will not scratch the surface upon which the fan is placed and will also have a tendency to cling to such surface and prevent any tendency of the fan to move or "walk" when in operation. Likewise, due to their resiliency, they will serve to clamp the base plate to the standard tightly. I do not claim herein the features incident to the connection of the base plate to the standard since the same have been made the subject matter of my co-pending application for fan bases, Serial No. 246,591, filed January 13, 1928.

The switch base and rheostat structure are mounted upon the base plate 11 in a manner which will now be described. The switch base 18 comprises a block of insulating material, which may be of porcelain or the like, having a central opening through which is inserted a pivot and securing member, such as the screw 19, upon which is pivoted a switch lever 20, the body portion of which is formed of conducting material. Upon the end of the switch member is a manipulating handle 21 of non-conducting material. This member is pivoted upon the member 19 between two washers 22 and 22^a and held in place and spaced slightly from the base plate by nuts 23 and 24 threaded upon the screw 19. Upon the switch base 18 are provided a number of contacts 25, 26 and 27, three of which

are shown in the drawings. These contacts may be conveniently formed of headed members, the heads of which form the contact posts, and the bodies of which are passed through openings in the switch base to have the lower ends 28, 29 and 30 turned laterally to engage below the switch base to hold the members in place. In order to prevent the lower ends of these members making electrical contact with the base plate 11, the upper surface of the latter may be covered by a sheet of insulating material 31, such as cardboard or the like.

The switch base and the structure carried thereby may be suitably secured to the base plate by lugs 32 and 33, which are struck up from the material of the latter and passed through openings in the switch base to have their upper ends 34 and 35 turned over the upper surface thereof, so that the latter is securely clamped to the base plate 11. These lugs 32 and 33 also pass through the insulating sheet 31 so that this member is likewise secured against movement.

25 Mounted on the upper surface of the switch base is a rheostat comprising a coil of resistance wire 37 wound spirally upon a spool shaped holder 38, which may be formed of a suitable insulating and refractory material, such as porcelain. The member 38 is provided with a spiral groove within which the coil 37 is disposed. The spool 38 is, in the form shown, hollow, and may be conveniently mounted upon the switch base 18 by having a central opening provided in the base 39 thereof to receive the screw 19, the nut 40 upon this screw serving to clamp the parts together.

One end of the coil 37 is connected by the wire 41 to the contact 25, and the other end is connected to the contact post 26 by the wire 42. A second wire 43 leads from the contact post 26 to the fan or electrically operated device designed to be controlled by the switch. Referring especially to Fig. 2, the wires 44 and 45 lead to the source of current which may be derived from an ordinary light socket, the wire 44 leading with the wire 43 directly to the fan. The wire 45 is connected to a conducting member 46 secured at one end below the nut 24 so that it makes electrical contact with the securing member 19 and with the conducting part 20 of the switch lever. It will be apparent, therefore, that one of the lead wires passes directly to the electrically operated device while the other is connected to the switch lever, and the current carried by the latter to one or the other of the contacts 25, 26 and 27.

60 The contact 27 is "dead", and when the lever rests upon this contact, as shown in dotted line position at A in Fig. 8, no current passes through the switch and the fan or other electrical device is inoperative. When, however,

65 the switch lever is moved over about the pivot

post 19 so that it rests upon the contact 26, as shown in full line position B of Fig. 8, the current passes through the switch lever 20 to the contact 26 and thence through the wire 43 to the fan. In this instance, the maximum amount of current will be delivered to the fan as the rheostat is without the circuit, and the fan will be operated at high speed. If, however, the lever is moved over to the dotted line position C of Fig. 8 so that the end rests upon the contact 25 the current will pass through the switch lever, the contact 25, the wire 41, resistance coil 37, and wire 42 to the contact 26, from whence it will be carried by the wire 43 to the fan.

It will be apparent that I have provided a switch base and rheostat of a very compact form and which may be constructed very cheaply, and which will at the same time be efficient in operation. Moreover, I have connected this base to the fan standard in a novel and secure manner so that the base plate 11 will be securely fastened to the standard by the rubber plugs or bushings which also serve as feet for the fan, as has already been described. The switch base and rheostat are of course assembled and secured to the base plate 11 before the latter is secured to the standard 10. After the parts have all been assembled, the operating portion 21 of the switch lever 20 will project through the slot 50 in the lower part of the standard 10, so that the switch may be conveniently operated.

While I have shown and described the preferred embodiment of my invention, it will be understood that it is not to be limited to all the details shown, but is capable of modification and variation within the spirit of the invention and within the scope of the appended claims.

What I claim is:

1. In a switch and rheostat structure, a flat base plate, an insulating plate mounted on and substantially coextensive with the upper surface of said base plate, a switch base of insulating material mounted on said insulating plate, a plurality of contacts carried on an upper surface of said switch base and having portions thereof extending downwardly through said switch base and outwardly between the latter and the insulating plate, and a switch lever pivoted above said switch base and adapted to engage said contacts.

2. In a switch and rheostat structure, a base plate, an insulating plate supported on an upper surface of said base plate, a switch base of insulating material mounted directly upon said insulating plate, a plurality of contacts on said switch base having portions thereof extending through said switch base and between the latter and said insulating plate, a switch lever pivoted above said switch base and adapted to engage said contacts.

tacts, and means for securing said base, insulating plate and switch base together, said securing means comprising slots in said insulating plate and switch base, and integral lugs struck from said base plate and extending upwardly through said slots and having their ends turned over the switch base to force said switch base and insulating plate towards the base plate and secure these parts rigidly together.

3. In a combined switch base and rheostat, an insulating plate, a pivot post rigidly secured to said plate and extending upwardly therefrom, contacts on an upper surface of said plate, a switch lever pivoted on said post above said plate and adapted to engage said contacts, a rheostat comprising a hollow spool of insulating material and a resistance element on said spool and connected with certain of said contacts, and means for securing said spool rigidly to said pivot post at a spaced interval from the switch base, said switch lever being pivoted on said post between said switch base and spool, the spacing of said insulating plate and spool permitting said switch lever to be freely operable on said post without interference from the spool and connections between the resistance element and contacts.

20 In witness whereof, I have hereunto set my hand this 25th day of January, 1927.

JOHN LANZ.
